(57) **CLAIM**

The ornamental design for a cap for a pouch, as shown and described.

DESCRIPTION

FIG. 1 is a top perspective view of a cap for pouches, showing our new design;

FIG. 2 is a front perspective view thereof;

FIG. 3 is a side perspective view thereof;

FIG. 4 is a front view thereof, the back view being a mirror image thereof;

FIG. 5 is a right-side view thereof, the left-side view being a mirror image thereof;

FIG. 6 is a top view thereof;

FIG. 7 is a bottom view thereof;

FIG. 8 is a perspective view thereof, showing the cap for a pouch in a position of use with an exemplary pouch;

FIG. 9 is a front view thereof, the back view being a mirror image thereof;

FIG. 10 is a right-side view thereof, the left-side view being a mirror image thereof;

FIG. 11 is a top view thereof; and,

FIG. 12 is a bottom view thereof.

The broken lines are shown for the purpose of illustrating both parts of the article as well as environmental subject matter of an exemplary pouch. None of the broken lines form part of the claimed design.

1 Claim, 7 Drawing Sheets
